UNITED STATES PATENT OFFICE.

SAMUEL S. MORITZ, OF DAYTON, WASHINGTON.

TAILOR'S MEASURING APPARATUS.

972,705.

Specification of Letters Patent. Patented Oct. 11, 1910.

Application filed August 16, 1909. Serial No. 512,978.

To all whom it may concern:

Be it known that I, SAMUEL S. MORITZ, a citizen of the United States, residing at Dayton, in the county of Columbia and 5 State of Washington, have invented certain new and useful Improvements in Tailors' Measuring Apparatus, of which the following is a specification.

This invention relates to tailors' measuring apparatus; and its object is the improvement of such devices whereby the same is rendered more simple and inexpensive in construction and more convenient to operate.

The invention consists in the novel construction and adaptation of parts, as will be hereinafter described and claimed.

In the accompanying drawings, Figure 1 is a perspective view of a measuring apparatus embodying my improvements; Fig. 2 20 is a side elevation of one of the attachments employed in the invention; Fig. 3 is a horizontal section taken through 3—3 of Fig. 2; Fig. 4 is a sectionalized perspective view of one of the elements of the invention and 25 Fig. 5 is a detail in section and broken away illustrating the preferred form of connecting certain elements of the device together.

The reference numeral 5 designates the base member of a frame having extending 30 upwardly therefrom two parallel posts 6 which are connected by tie-bars 7. Rigidly secured to the bars is an upright rod 8 which is desirably disposed to be in proximity to a vertical plane medially of posts 6. The 35 bar 8 may advantageously be made of three pieces, as illustrated, and is characterized by having a series of marks 9 which are graduated so as to indicate heights or distances with a conventional scale from the platform 5' of said base. The lower of the bar parts 8 is offset transversely from the center of the frame and may be connected with the bar-part next above by welding or otherwise; while the securement between 40 the bar-parts and the aforesaid tie-bars may be had in any suitable manner, as for example, by abutting the ends of the former against the respective tie-bars and employing fastening screws which extend through 45 the latter into screw-threaded holes provided in the several parts of the bar 8, or by bolts extending through the tie-bars and lugs such as shown with respect to the upper part of the bar 8. Slidably mounted upon the above 50 mentioned off-set part of bar 8 is a sleeve 10 to which is pivotally connected, by a pin 11

(Fig. 3) for vertical oscillatory movement, a hollow block 12 which affords a housing for a bar 13, which, through the off-setting of a part of the bar 8 with which it is connected, is positioned at equal distances from the posts 6 or at the mid-width of the frame. 16 and 17 represent set screws respectively employed for securing the sleeve 10 at various heights to the bar 8 and the bar 13 in 60 adjusted position within the block 12. The pin 11 is desirably located adjacent to the rear edges of the sleeve and block while, near the front edges of the former, a spring-pressed bolt 14 is utilized to socket in a hole 65 15 provided in the block when the latter is in operative position, as indicated by full lines in Fig. 2, and thus maintain the bar 13 horizontally. This bar 13 is designed for designating the height of a person's crotch 70 75 from said platform when standing thereon, and with the bar 13 horizontal and at the proper height, through manipulating the sleeve 10 upon the bar 8 the measurement can be had from the registering mark corresponding with the top of a recess 18 provided in the sleeve and which is in the same plane with the top edge of the bar 13. When this measurement is obtained the bolt 14 is disengaged from the block and bar 13 swings 80 85 down to be in the position indicated by broken lines in Fig. 2 and out of the way for subsequent measuring operations.

On the bar 8 are also provided two blocks 19 and 20 which are each provided with an 90 aperture 21 having openings at the top, bottom, and the front and back sides to accommodate both the bar 8 and the respective horizontal bars 22 or 23. By thus forming a single chamber in each of the blocks 19 95 and 20 for the horizontal bars as well as for the vertical bar a single clamping screw 24 may be used for one of the blocks and a similar screw 25 for the other, a matter of considerable convenience to the operator. 100 The bar 22 is employed for various measurements of a person's back, as is also the bar 23 while the latter will in addition serve to give his height.

Fitted to slide upon the posts 6 are sleeves 105 26 provided with housings 27 for laterally extending bars 28. Each of the latter has a sleeve 29 slidable thereupon to respectively carry forwardly extending arms 30 which, in turn, have upwardly extending arms 31 110 slidably attached thereto. The arms 30 are for determining the elevations of the arm-

pits of a person being measured, as well as the heights of the hips by having the upper and lower edges of these blades, upon occasion and through the proper shifting of the 5 sleeves 26, bear against such parts of the person's form. To determine these measurements with reference to the bar 8, I provide upon the adjacent ends of the bars 28 attachments 32 which are each provided with 10 fingers 33 and 34 which are respectively disposed to be in the planes of the top and bottom edges of the respective arms 30 and in such relation to the bar 8 as to designate thereon the heights of said edges.

15 The operation of the invention may be described as follows: A person to be measured stands on the platform 5' and his height is taken by the bar 28 with reference to the scale upon the rod 8. The elevation of the 20 crotch of the legs, for the inseams of the trousers, is taken by the bar 13 with reference to the scale upon the rod 8 and when this measurement is had the bar may be turned down, as previously explained. The 25 bars 22 and 23 may now be employed in ascertaining the curvature of the subject's back by employing the scale markings which are respectively provided thereon in connection with the scale markings upon the rod 30 8 for locating heights at which these measurements are taken. The sleeves 26 are next moved into position to present the lower edges of bars 30, when these bars are suitably adjusted with respect to the bars 28, 35 against the hips and the pointers 34 of the respective parts will indicate the height of each of the hips while the other pointers 33 will give the height for the top edge for the trouser's waistband. The sleeves 26 are then 40 elevated to carry the bars 30 into contact with the respective arm-pits of the person being measured, the bars 30 being accordingly shifted, and the upright bars 31 brought against the front of the shoulder-blades. With the last described parts thus 45 adjusted the heights of the arm-pits are read upon the bar 8 through the designating pointers 33; the distance apart by the scales upon the bars 28; and the thickness of the 50 shoulder-blades by the relative positions of the bars 31, as indicated by scales upon the respective bars 30. It is to be noted that the pointers 33 and 34 of the attachments 32 not only show by their relative positions any 55 irregularities between the dual parts of a person's body but also serve to indicate upon the scale of rod 8 the precise elevations of the same from the supporting platform.

60 What I claim as my invention, is—
65 1. The combination of a standard consisting of a pair of posts, a tie-bar for connecting the lower ends of said posts together, a tie-bar secured to the posts at a point removed from their lower ends, a measuring bar formed of a plurality of sections, certain

of said sections being secured together and further interposed between and secured to said tie-bars and the other of said sections being secured upon the upper of said tie-bars, an adjustable measuring device mounted 70 upon one of the sections interposed between the tie-bars, an adjustable measuring device mounted upon another of the sections interposed between the tie-bars, an adjustable measuring device mounted upon that section carried by the upper tie-bar, an adjustable duplex measuring device carried by one of said posts and associating with said measuring bar, and an adjustable duplex measuring device carried by the other of said posts 75 and associating with said measuring bar.

2. A tailor's measuring apparatus comprising a frame embodying a pair of posts, a tie-bar connected to said posts at a point removed from their lower ends, a tie-bar connecting the upper ends of said posts together, an off-set measuring bar connected to said tie-bars, and projecting above the upper of said bars, measuring devices carried by the posts of said frame and associating with said measuring bar, a pair of measuring devices carried by the measuring bar and interposed between said tie-bars, and a measuring device carried by said measuring bar and arranged above the upper of said 90 tie-bars.

3. A tailor's measuring apparatus comprising a frame embodying a pair of posts, a tie-bar connected to said posts at a point removed from the lower ends thereof, a tie-bar connecting the upper ends of said posts together, a measuring bar connected to and projecting above said tie-bars, that part of the measuring bar interposed between the tie-bars off-set at a point intermediate its ends, an adjustable sleeve carried by the lower part of the measuring bar, a block pivoted to said sleeve and carrying a short bar, means carried by the sleeve and engaging said block for maintaining said short 105 bar at right angles with respect to the measuring bar, an adjustable measuring device carried by the upper portion of the measuring bar and below the upper tie-bar, an adjustable measuring device carried by the 110 measuring bar and above the upper tie-bar, an adjustable measuring device carried by one of the posts of the frame and associating with the measuring bar, and an adjustable measuring device carried by the other post 115 of the frame and associating with the measuring bar.

4. A tailor's measuring apparatus comprising a frame embodying a pair of posts, supporting means for said posts, a tie-bar connected to said posts in proximity to their lower ends, a tie-bar connecting the upper ends of said posts together, a measuring bar supported by the lower tie-bar and connected to and projecting above the upper 120 125 130

tie-bar, that portion of the measuring bar between the tie-bars being off-set, an adjustable measuring device carried by the lower portion of the measuring bar, an adjustable

5 measuring device carried by the upper portion of the measuring bar, and below the upper tie-bar, an adjustable measuring device carried by the measuring bar above the

upper tie-bar, and an adjustable measuring device carried by each post of said frame 10 and having an inwardly-extending element associating with said measuring bar.
